RECORD CHANGER MECHANISM FOR
PHONOGRAHSHoward A. Roe, Elyria, Ohio, assignor to The
General Industries Company, Elyria, Ohio, a
corporation of Ohio

Application January 20, 1942, Serial No. 427,468

7 Claims. (CL. 274—10)

My invention relates to record changing mechanism for phonographs and relates more particularly to record changing mechanisms of the general type wherein a stack of records normally supported above a phonograph turntable are automatically lowered one at a time onto the uppermost surface of the turntable or onto the uppermost surface of any uppermost record at the time disposed on the turntable for reproduction by the phonograph reproducer adapted to traverse and reproduce the uppermost record during the playing thereof.

It is an object of my invention to provide an improved mechanism of the type described which may be economically manufactured and which will be efficient in use.

Another object of my invention is to provide an improved record changer mechanism of the type described wherein improved means are provided to operate the record supporting and lowering means of the mechanism.

Another object of my invention is to provide an improved record changer mechanism and more particularly the motor driven means employed therein to perform the record changing functions whereby such functions may be quietly and efficiently performed by the mechanism by power supplied from a phonograph turntable driving motor which by virtue of my invention may be of very low power.

Another object of my invention is to provide an improved record changer mechanism wherein the mechanical functions are so performed as to avoid any large sudden loads being applied to the driving motor for the mechanism, to minimize the power required from such motor and therefore to minimize the size and cost of the motor.

Another object of my invention is to provide an improved power take-off for driving the record changing mechanism and an improved relationship between a motor driven element and said power take-off, whereby said power take-off may be quietly and efficiently associated with and disassociated from the said motor driven element.

Another object of my invention is to provide an improved phonograph mechanism of the type described whereby the required movements of the tone arm at the conclusion of the playing of one record and prior to the playing of the next record are expeditiously and efficiently and quietly effected.

Another object of my invention is to provide an improved power take-off unit for the record changing cycle.

Other objects of my invention and the invention itself will become apparent to those skilled in the art by reference to the accompanying drawings and the following description of the embodiment of my invention illustrated therein.

In the drawings:

Fig. 1 is a plan view of the phonograph record changer of my invention, partially broken away to illustrate the turntable drive;

Fig. 2 is a bottom plan view of the mechanism of Fig. 1;

Fig. 3 is a horizontal section as indicated by the line 3—3 on Fig. 6;

Fig. 4 is a fragmentary bottom plan similar to a part of Fig. 2 but illustrating the parts in a different position;

Fig. 5 is a horizontal section as indicated by the line 5—5 on Fig. 6;

Fig. 6 is a vertical sectional view as indicated by the lines 6—6 in Fig. 2; and

Fig. 7 is a vertical section as indicated by the lines 7—7 in Fig. 2.

The drawings hereof illustrate an embodiment of my invention, which is merely one example of the manner of practicing the invention.

In the embodiment illustrated, the phonograph mechanism shown is one wherein the driving motor drives the turntable by a friction driving connection between the motor shaft and the peripheral turntable flange, but it is to be understood that my invention is applicable to such a mechanism wherein the phonograph turntable is driven by the motor in any suitable way as, at present, well-known in the art.

As shown in the drawings, a base plate 10 is provided upon which are mounted the motor, turntable, tone arm, and record changing and ancillary mechanisms of my invention, the entire unit being adapted for mounting in a suitable phonograph cabinet by means of bolt holes 11. The base plate supports, as stated, the turntable 12 which is drivingly secured on a spindle 13 as by a pin and slot connection 14, shown at Fig. 7.

45 To clarify the following description of the operating parts of the improved phonograph mechanism described herein a brief statement as to the cycle which the illustrated mechanism is adapted to perform follows:

As the reproducing tone arm of the phonograph reaches the termination of a record which it has been playing, the tone arm trips a latch and enables a power take-off, at the turntable spindle, to drive a master gear, which gear carries cams and pins which operate various cam

followers and levers which, in turn, lift the tone arm from the record, swing it off to the side, drop a succeeding record onto the turntable, swing the tone arm back to the record, lower it to the starting groove of the record and finally disengage the power take-off whereby the mechanism remains idle during the playing of the record. This mechanism is also adapted to perform various subsidiary functions such as the accommodation of records of differing sizes and the automatic interruption of the power supplied to the motor and includes the motor drive for the turntable as well as various manual controls, all of which will be more fully explained by the following description of the specific mechanical parts involved.

The turntable 12 is suitably rotated by a synchronous motor 15, mounted below the base plate by means of bolts 15a, as through the medium of a rubber tired idler wheel 16 slideably mounted so as to contact both the motor spindle 17, projected through an opening in the base plate, and the turntable rim 18. As best illustrated in Figs. 1 and 7, the idler wheel spindle 19 is carried by two axially spaced discs 20 and 21 centrally perforated to permit the mounting of the spindle thereon, said discs being free to slide on the upper and lower surfaces, respectively, of a plate 22 mounted on the base plate 10, rounded protuberances 23 being preferably formed on the discs 20 and 21 to decrease friction. A light tension spring 24 secured to the spindle 19 and extending therefrom to an anchorage on the base plate 10 maintains the idler wheel in driving contact with the turntable rim and the motor spindle, the directions of rotation being such that the wheel tends to wedge between the motor spindle 17 and the turntable rim 18, thus ensuring an efficient drive. An enlarged aperture 25 in the plate 22 allows the necessary freedom of movement of the wheel spindle 19.

The above described turntable driving means, whereby power is communicated from the motor to the turntable, is but one of a number of different arrangements which may be employed.

Power from the motor to operate the record changing mechanism is preferably derived from the turntable spindle, as the latter is being rotated as just described.

As best seen in Figs. 5 and 7, the turntable spindle 13 is provided, intermediate its bearings in the supporting bracket 28, with a pinion 29 with which a power take-off device 30 is adapted to engage. This device 30 comprises an elongated plate 31 pivoted intermediate its ends on a stud 32 carried by a sub-base 33 supported, as by posts 34, below the base plate 10.

A train of gears is carried by the plate 31 and consists of a compound gear, rotatable on the pivot stud 32, one member 35 of which meshes with an idler gear 36 which, in turn, meshes with a gear 37. A spring 38 anchored to the sub-base 33 and to the plate 31 tends to rock the take-off device in a counter-clockwise direction, Fig. 5, and to engage the gear 37 and the pinion 29 on the turntable spindle 13. The angle between the center to center line of the gear 37 and the stud 32 and that of the gear 37 and the pinion 29 is preferably slightly less than 90°, preferably by an amount substantially equal to the pressure angle of the gear teeth in such manner as shown, wherein there is a minimum of friction under load, the gears tending neither to pull together or to disengage.

The above angle given as preferably slightly less than 90° may be varied over a range preferably between 50° and 90°, the particular angle illustrated and above referred to being found, however, to achieve best results.

The power take-off is normally, when the record changing mechanism is not in operation, held out of engagement by a latch 40, pivoted on the sub-base at 40a, the tooth 41 of which engages an upturned lip 42 on the far end of the plate 31. After the latch is tripped by means later described the lip 42 engages an abutment 43 on the latch 40 beyond the tooth 41 as the spring 38 rocks the plate 31 and the gears 29 and 37 come into meshing engagement. A spring 44, secured to the latch and anchored on the sub-base 33, maintains the latch in contact with the lip 42 in either of its two positions.

As previously mentioned, the tone arm of the phonograph operates to trip the latch 40 just described and thus to engage the power take-off.

The reproducing tone arm 50, Fig. 6, is pivotally mounted as at 51 on a rotatable head 52, for movement in a vertical plane to and from the record to be played on the turntable. A tension spring 53 is preferably employed to counterbalance the greater part of the weight of the tone arm and is secured as at a to the outer end of the tone arm and at b to the head 52, an adjustable stop 54 being used to limit the downward movement of the arm 50. The head 52 which carries the tone arm 50, spring 53 and stop 54, is, in turn, carried by a hollow spindle 55 to which it is secured as at 56. The spindle 55 is supported, in turn, by and journaled in a rigid hollow post 57 which extends through and is secured to the base plate 10. A flat sector 60 is drivingly carried by the spindle 55 below the post and thus partakes of the oscillations of the tone arm.

Referring now to Fig. 5, a trip arm 61 is shown pivoted at one end upon the sector at 62 and slideably supported at the other end within a slotted plate 63 carried by the sub-base 33.

Normally, frictional contact with the sector 60 by the trip arm 61 maintains the said trip arm 61 against the end of the slot, as illustrated by the broken line position 61a, during the traverse of the tone arm across the record. Near the termination of the record, however, the sector in swinging inwardly pushes the trip arm into contact with a light leaf spring 64 which cams the trip arm inwardly to contact the surface 65 thereof against a knife edge 66 carried by the latch 40, previously described.

As the playing is about to terminate, and the tone arm needle approaches the end of the record groove, the first of a series of ratchet teeth 67 on the arm slips past the knife edge, and upon any subsequent reversal of movement of the trip arm the particular ratchet tooth then in contact with the knife edge of the latch pulls the knife edge to the left, as shown in Fig. 5, and trips the latch 40 to initiate the power take-off associated therewith. Such reversal of movement might either be due to the moving of the pick-up needle of the tone arm 50 by the terminal oscillating groove 68, Fig. 1, usually provided on the record or by its idle meandering after leaving the playing groove. An additional means of tripping the latch 40 is provided by a cam plate 69 secured to the trip arm 61 and adapted to engage a pin 70 carried by the latch. Continued inward swinging of the tone arm, due for in-

stance to the spiral terminal groove sometimes provided, carries the cam toward the right and urges the pin and thus the latch 40 in tripping direction.

The power take-off mechanism is adapted to drive a master gear 75 which, in turn, drives the record changing and tone arm swinging mechanism. As best seen in Fig. 5, the second member 76 of the compound gear mounted on the pivot stud 32 is constantly in driving engagement with the gear 75, which rotates freely on a fixed stud 77 carried by the sub-base 33.

Concentrically mounted upon the gear 75 is a cup shaped cam 78 which operates to raise and lower the tone arm. An arm 79, Fig. 6, is centrally pivoted upon the sub-base and is formed as a cam follower 80 at one end, riding on the lower edge of the cam 78. An adjustable contact 81 carried by the opposite end of the arm supports a rod 82 slideable within the hollow spindle 55. Normally, the cam follower rests in a notch 83 of the cam and the rod remains at its lowered position. As soon as the power take-off is engaged, however, the cam rotates and the arm 79 is rocked to lift the rod 82 which, in turn, contacts the lower surface of the tone arm and lifts it from the record.

Subsequent to the raising of the tone arm, it is swung off to the side clear of the edge of the record. As will be seen in Fig. 5, the sector 60 is provided with an extension 85 which projects into the path of a roller pin 86 on the master gear. As the gear revolves, the pin engages this extension, swinging it from the full line position to the extreme broken line position 85a and thus swinging the tone arm aside. As the sector 60 is swung toward its extreme position 60a, it returns the trip arm 61 to the left. To free the ratchet teeth 67 from the knife edge 66 for this return movement, a cam 87 carried by the master gear pushes outwardly on a projection 88 secured to the trip arm.

Referring now to the record changing operation, it will be noted in Figs. 1 and 6 that two vertical hollow posts 90 are provided at diametrically opposite points on the base plate and carry record stack supporting devices at their tops. To accommodate records of various diameters, these posts are carried by standards 91a and 91b pivoted about bosses 92 projecting downwardly through the base plate 10. The position of the standard 91a is selected by the operator, being guided by a pointer 93 on the standard in conjunction with suitable indicia 94 on the base, and through a suitable linkage the standard 91b is caused to assume a similar position. This linkage comprises a parallelogram arrangement in which a cross bar 95, Fig. 2, below the base plate is pivoted at one end to a boss 96 depending from the standard 91a through a slot in the base and at the other end to an arm 97 drivingly secured to the pivot boss 92 of the standard 91b. As illustrated in Fig. 2, this cross bar may be suitably offset or bent to clear the motor or other parts.

The stack supporting devices, previously mentioned, each comprise three plates 100, 101 and 102, rigidly secured to a spindle 103 rotatable within the respective post 90. The plate 100 normally projects within the periphery of the records and hence serves as a support for the stack 5 above and clear of the tone arm. The plate 101 is of comparatively flexible material and is formed as an arcuate tongue which, upon rotation of the spindle 103 by means later described,

is adapted to enter the stack between the lower two records. Upon further rotation, the first plate 100 is withdrawn, dropping the lowermost record. The remainder of the stack is at this time supported upon the tongue which is backed up, except at its unsupported free end, by the relatively rigid third plate 102. After approximately a quarter of a revolution of the spindle 103, the direction is reversed and the flexible tongue is withdrawn, the stack being gently lowered thereby to the supporting plate 100 which has again come below the stack.

The rotation of the stack support spindle 103, just described, is derived from the master gear 15. As shown in Figs. 2 and 6, short cranks 105 are secured to the lower end of the spindles and are linked, as at 106, to arms 107 of bellcranks pivoted at the axes of the standard bosses 92. The other arms 108 of the bellcranks are interconnected by a cross link 109 which is reciprocated by the master gear. The cross link 109, best seen in Fig. 3, is provided with two lips 110 and 111 which are engaged by pins 112 and 113 projecting upwardly from the master gear 75. As the gear is rotated by the power take-off, the pin 113 nearest the axis engaged the lip 110, as indicated by broken lines at 113a, Fig. 2, and moves the link 109 slowly to the left to cause the tongues 101 to gently enter the stack. Thereafter, pin 112, which is at a greater distance from the axis and hence moves more rapidly, engages the lip 110 and continues the movement at a faster rate so that the link may move the necessary distance in its allotted portion of the cycle. As pin 112 leaves the lip 110, the inner pin 113 engages the lip 111, as shown in Fig. 3, and continued rotation of the master gear returns the crosslink slowly to the right to restore the normal stack support with a minimum of noise and wear.

As will be seen in Fig. 6, the pin 112 is the shorter of the two and hence does not engage the lip 111, which is shallower than lip 110. When the power take-off is disengaged at the end of the cycle, by means to be described, the master gear comes to rest with the pin 113 contacting the lip 111 on dead-center relative to the direction of movement of the crosslink 109, as shown in Fig. 2, thus locking the linkage and the stack supports against inadvertent displacement.

Following the dropping of the record, as just described, the tone arm is swung inwardly and lowered to the rim of the record. The same cam 87, on the master gear, which coacts with the projection 88 of the trip arm also engages an arm 115 of a bellcrank pivoted on a bracket 116. The other arm 117 of the bellcrank engaged a pin 118 on the sector 60 and, upon being rocked by the cam 87, thereby swings the sector 60 inwardly to return the tone arm. As the sector 60 was previously swung outwardly to the extreme position 60a, as described hereinbefore, the pin 118 moved the bellcrank to the broken line position 115a-117a. The cam 87, therefore, now swings it to the position 115b-117b to move the sector to the position 60b and the tone arm 50 to the rim of the record. As the master gear continues its rotation, the cam follower 80, previously described, rides into the notch of the cam 78, allowing the tone arm to descend and the pickup needle to engage the margin of the record. Thereupon a light leaf spring 120 carried by the master gear urges the bellcrank arm 115b outwardly a small amount to cause the needle to ride into the initial playing groove of the record.

As the playing grooves carries the tone arm inwardly, the bellcrank is rocked idly by the pivot pin 62 to the full line position 115-117 of Fig. 5. An adjustable stop 121 may be provided to limit the extreme inward position of the sector 60.

When playing a smaller size record the tone arm must of course be swung inwardly a greater amount to reach the margin of the record. To provide for this, the bracket 116 which supports the bellcrank, just described, is mounted on the crossbar 95 which imparts the selected positioning to the standard 91b. Thus, when the standards are positioned to accommodate the smaller records, the bracket 116 is moved to the broken line position 116d of Fig. 5 and the bellcrank when swung by the cam 87 takes the position 115d-117d. The sector is thereby moved to the position 60d, which will be noted to be slightly inward from the position 60b corresponding to the larger records.

The final function of the master gear is the disengagement of the power take-off and thus the cessation of its own rotation. As the roller pin 86, Fig. 5, on the gear nears its final position, it engages a pawl 125, pivoted at 126 upon the power take-off plate 31. The roller 86 rocks the pawl in a clockwise direction, Fig. 5, against the action of a tension spring 127 anchored on the plate 31.

Due to the hooked form of the pawl, the angle of contact with the roller 86 at first tends to keep the take-off in its engaged position but eventually the roller swings the pawl 125 to a position such as that indicated by the broken lines where the force of the spring 127 is sufficient to overcome that of the holding-in spring 38. The curved end of the pawl then is forcibly cammed arcuately outward about the roller, forcing the plate 31 in a clockwise direction about its pivot 32 and causing the lip 42 to leave the abutment 43 on the latch 40. A snapping action is then effected, by the forcible camming of the pawl resulting in the striking of its arm 128 against a stop 129 on the plate, which causes the lip 42 to strike a rubber-covered stop 130 on the latch. This striking is in such a direction as to assist the latch spring 44 in swinging the tooth 41 into the path of the lip 42 as the lip rebounds and thus insures the latching action thereof. The power take-off at this time assumes the disengaged position illustrated in full lines in Fig. 5 and the master gear reaches the end of its cycle.

When desired, the mechanism may be preset so as to switch off the electric motor at the termination of the record then being played. For such purpose, a bar 135, Fig. 2, is connected to a short crank 136 carried by the same spindle 137 of the electric switch which carries the manual button 138, Fig. 1. A notch 139 in this bar is adapted to be engaged by a projecting ear 140 on the crank 105 of the record dropping linkage, so that at the appropriate time during the cycle the bar 135 will be pulled to turn the switch to its "off" position. Normally, the bar is held out of engagement with the ear 140 as shown in Fig. 4, by a link 141 pivoted to a rocker arm 142 carried by a rod 143. The rod is journaled in the standard 91b and may be selectively rotated, by means of a handle 144, Fig. 1, into either of two positions.

In the normal position of Fig. 4, a projection 145 on the rocker arm 142 bears against the post 90 and is maintained in such position by a tension spring 146 extending between the rocker 75 the appended claims.

arm and an anchorage 147 on the link 106. When it is desired that the motor should stop at the completion of the record, the handle 144 is turned to the full line position shown in Fig. 1 and the rocker arm 142 thus to its position shown in Fig. 5. The rocker arm now lies against the pivot of the link 106 on the crank 105 and is maintained there by the spring 146 which now acts on the opposite side of the rocker arm pivot 143, thus holding the notched portion of the bar 135 in the path of the ear 140. The freedom of motion allowed by the link 141 permits the switch to be turned on or off manually regardless of the position of the remainder of the mechanism.

If desired, a record may be rejected at any time during the playing thereof and the following record of the stack substituted therefor. To accomplish this, a manual button 150, Figs. 1 and 7, is provided which is carried at the forward end of a trip lever 151 pivoted on the sub-base 33 as at 152. The rear end of the trip lever 151 is inclined upwardly at 153 whereby, consequent to the depression of the button, the lever 151 cams the pin 70 carried by the latch 40 inwardly. The latch 40 is thus tripped to engage the power take-off regardless of the position of the tone arm at the time and the mechanism thus goes through its cycle to drop the next record. The button 150 also operates as a starting button to drop the first record of a new stack.

Also, if desired, the phonograph may be set for manual operation. The positioning pin 160 carried by the standard 91a, Figs. 1 and 6, may be withdrawn and the posts swung to their outermost positions clear of the largest records. In so doing, an extension 161, Figs. 2 and 7, carried by the crossbar 95 between the standards engages an upturned end 162 of the power take-off plate 31 and by moving such end 162 to the left, Fig. 2, maintains the gears 29 and 31 out of engagement. The tone arm 50 may then be manipulated by the operator at will since the tripping of the latch 40 by the trip arm 61 does not allow the power take-off to engage. An extension 165 on the tone arm sector 60 may be provided to contact the fixed post 34 at the extreme outer position of the sector and hence may act as a stop to limit the outward swing of the tone arm.

A friction brake may also be provided for the outward swing of the tone arm, as shown in Figs. 2 and 6, wherein a bent spring 166 is secured to the tone arm lifting lever 79 and is provided with a pad of felt or the like at 167. Normally, the brake is out of contact with the sector 60 but, when the tone arm is raised for outward swinging, sufficient braking action is introduced to prevent its overtraveling due to inertia.

The improved record changer mechanism above described is one which, because of the design of the motion communicating mechanism including the improved power take-off, wherein a very small motor of low power may be employed to drive the phonograph turntable, and wherein the motion transmitting mechanism is operated smoothly and without any sudden increases in load imposed upon the motor, results in a highly efficient quiet operation of the mechanism and eliminates the investment for the usual larger motor.

Having thus described my invention in a particular embodiment, I am aware that the same may be modified within the range of mechanical skill, and may take widely varying forms within the purview of my invention and the scope of

I claim:

1. A power take-off for a phonograph record changing mechanism for phonographs of the type comprising a turntable, a turntable motor, a turntable spindle, a pinion carried by said phonograph turntable spindle, a phonograph needle-carrying tone arm, a pair of record supporting posts arranged adjacent said turntable, said posts having plate means associated therewith, said plates being movable to singly supply new records upon the turntable below, said power take-off comprising an arm pivoted intermediate its ends upon a base structure for said phonograph record changing mechanism, a train of intermeshed gears carried by said arm comprising a compound driven gear, an intermediately disposed idler gear and a driving gear adapted to engage the pinion carried by the said phonograph turntable spindle, said pinion being in constant driven relation with the shaft of the phonograph motor, a master gear carried by said base structure, said compound gear adapted to further engage the master gear rotatable to communicate timed actuating motion to record changing controller means for raising, swinging and lowering of the tone arm associated with the phonograph turntable, and for communicating movement to said movable plates to superposition new records on the turntable after any outward swinging movement of the raised tone arm with respect to the turntable, said driving gear journaled on said arm in spaced relation to said driven gear axis, a spring adapted to exert pressure tending to swing said arm laterally forwardly to mesh said driving gear element with said motor driven gear pinion, a latch normally holding said arm in an outwardly swung position, means operated by said tone arm when its needle traverses the terminal groove of a played record to release said latch, to initiate the power take-off and associated master gear, to actuate the above said controller means and record supports, and the included angle defined by the axis of oscillation of said arm of rotation, of rotation of said driving gear element, and of rotation of said motor driven gear pinion being substantially less than 90°.

2. A power take-off for a phonograph record changing mechanism for phonographs of the type comprising a turntable, a turntable motor, a turntable spindle, a pinion carried by said turntable spindle, a phonograph needle-carrying tone arm, a pair of record supporting posts arranged adjacent said turntable, said posts having plate means associated therewith, said plates being movable to singly supply new records upon the turntable below, said power take-off comprising an arm journaled on said base and oscillatable about its journal, energy storage means associated with said arm, a set of relatively meshed gear pinions individually journaled on said arm, a master gear carried by the base, a first of said gear pinions so disposed as to remain meshed with said master gear during oscillatory movements of said arm, a second of said gear pinions adapted to be bodily laterally moved into and out of mesh with said motor driven pinion, said set of pinions adapted when said second and said motor driven pinion are meshed to communicate rotary motion to said master gear, a latch for holding said arm in a position wherein said second pinion is disengaged from said motor driven pinion, latch engaging means operable responsive to an abnormal non-record playing swinging movement of said tone arm when it is in a low- 75

ered record playing level of altitude at the conclusion of a record playing period to operate said latch to release said arm from its locked position whereby said stored energy means associated with said arm resiliently exert pressure on said arm to swing it to a position wherein said second pinion is meshed with said motor driven pinion, said master gear being thereby driven to sequentially engage means associated with said tone arm to lift said tone arm out of engagement with said turntable and to swing said tone arm outwardly and laterally of said turntable, means associated with said oscillatory posts to singly supply new records to the phonograph record supporting turntable, means to swing said tone arm inwardly towards the turntable and to lower said tone arm to the rim of the record placed thereon, and means carried by the power take-off means effective to force the arm about its pivot and to place it in a disengaged position with respect to the master gear.

3. A power take-off for operating the elements of a record changing phonograph cyclically operable automatically at the end of a record playing period to superpose a new record from a supply stack over the played record on the turntable and to effect proper movements of the phonograph tone arm to permit the unobstructed movement of each new record supplied from the stack to the turntable comprising a master gear for driving said elements, an oscillatory arm, a set of intermeshed pinions carried by said oscillatory arm comprising a first pinion journaled on the arm in such a position as to constantly mesh with the master gear rotatable to communicate timed actuating motion to the said elements of the record changing mechanism and to effect proper movements of said tone arm, said master gear being mounted upon the base of said phonograph, and a second pinion carried by said arm adapted to be bodily laterally swung during oscillatory movements of said arm, a motor for said phonograph and a pinion constantly driven thereby, said pinion positioned so to mesh with said second pinion upon swinging of the arm forwardly, a spring resiliently exerting pressure tending to swing the said arm forwardly, a latch restraining forward arm movement and trigger means operable by said tone arm when moved laterally by the effect of the tone arm needle being led into the terminal groove of a played record at the end of the playing means, said trigger means engageable with said latch to release said power take-off arm therefrom to initiate a cycle of operation of said master gear.

4. A clutch controlling mechanism adapted for use with a record changing mechanism for an automatic phonograph wherein the reproducer tone arm thereof is periodically moved out of contact with a previously played record and out of the intended path of a record which is subsequently positioned for playing upon the phonograph turntable and wherein the tone arm is then restored to starting position in contact with said subsequently positioned record, said records being supported in a stack upon fixed support means disposed adjacent said turntable, a source of power, a base for said phonograph, a motor drive pinion rotatably carried by said base, said clutch controlling mechanism periodically effecting driving of said record changing mechanism through power derived through said motor drive pinion and a gear mounted upon said base by means of a second and third pinion carried by a clutch carrier arm oscillatably mounted on said

base for driving said mechanism during non-record playing intervals, the said second pinion journaled on the arm co-axially with the axis of oscillation of said arm, the said third pinion disposed in driving relation to said second pinion and rotatably mounted on said arm at a point thereon laterally spaced from the arm axis, and adapted to be swung upon a forward oscillatory movement of the arm into mesh with said motor driven pinion, a stepped oscillatory latch for said arm adapted to retain said arm against either of alternate successive step stops in either of two alternate positions of its swinging path, corresponding to the relative lateral spacing of said steps, means to swing said latch to release the arm from a first step, spring means biasing said arm towards said second step for moving the released arm forwardly to its second step position wherein said third pinion is swingingly advanced into mesh with said motor driven pinion to effect driving of said gear through said second pinion, a snap action arm resetting mechanism for the arm comprising trigger and finger elements, one of said elements associated with said arm and another of said elements moved by said gear at the conclusion of a single cycle of rotation thereof to engage the other said element, to positively restore said arm to its initial first step latched position, and to relatively disengage said motor driven and third pinions, said latch oscillating means comprising a member movable by the phonograph tone arm when the needle thereof is carried into the terminal groove of a played record to rock said latch.

5. The mechanism substantially as set forth in claim 1, characterized by the provision of means to restore the recited pivoted arm to its recited outwardly swung latched position, said restoring means comprising an element carried on the arm and having a pawl portion which is normally resiliently constrained to extend laterally of the pivoted arm inwardly over the peripheral border portion of the recited rotatable master gear, and a contactor, said contactor carried on said gear and adapted, when said master gear is rotated, to engage the extended pawl and progressively to forcibly deflect it outwardly in the direction of circular motion of said contactor and outwardly of its path, whereupon, by a thumb-and-finger snap-action, said pawl is adapted to reactively resiliently snap towards its normal position, with its advanced end rapidly traversing the outermost surface of said contactor against which it cammingly resiliently reacts, thereby suddenly communicating reactive lateral pressure upon said arm to cause it to be swung to its recited outward latching position and to disable the recited power take-off and to re-condition the recited mechanism of said

claim for the recited operation thereof, in response to the recited movement of said tone arm.

6. The mechanism substantially as set forth in claim 2, characterized by the provision of means to restore the recited pivoted arm to its recited outwardly swung latched position, said restoring means comprising an element pivotally carried on the arm and having a pawl portion which is normally resiliently constrained to extend laterally of the pivoted arm inwardly over the peripheral border portion of the recited rotatable master gear and a contactor, said contactor carried on said gear adapted when said master gear is rotated to engage the extended pawl and progressively to forcibly deflect it outwardly in the direction of circular motion of said contactor and outwardly of its path, whereupon, by a thumb-and-finger snap-action, said pawl is adapted to reactively resiliently snap towards its normal position with its advanced end rapidly traversing the outermost surface of said contactor against which it cammingly resiliently reacts, thereby suddenly communicating reactive lateral pressure upon said arm to cause it to be swung to its recited outward latching position and to disable the recited power take-off and to re-condition the recited mechanism of said claim for the recited operation thereof, in response to the recited movement of said tone arm.

7. The mechanism substantially as set forth in claim 2, characterized by the provision of means to restore the recited pivoted arm to its recited outwardly swung latched position, said restoring means comprising an element pivotally carried on the arm and having a pawl portion, a spring resiliently constraining said pawl to such a normal rotative position to cause it to extend laterally of the pivoted arm inwardly over the peripheral border portion of the recited rotatable master gear, and a contactor, said contactor carried on said gear adapted when said master gear is rotated to engage the extended pawl and progressively to forcibly deflect it outwardly in the direction of circular motion of said contactor and outwardly of its path, whereupon, by a thumb-and-finger snap-action, said pawl is adapted to reactively resiliently snap towards its normal position, said spring constraining said pawl to cause its end to rapidly traverse the outermost surface of said contactor against which it cammingly resiliently reacts, thereby suddenly communicating reactive lateral pressure upon said arm to cause it to be swung to its recited outward latching position, and to disable the recited power take-off and to re-condition the recited mechanism of said claim for the recited operation thereof, in response to the recited movement of said tone arm.

HOWARD A. ROE.
